UNITED STATES PATENT OFFICE.

JOHN IRWIN FULLWOOD, OF CEDARTOWN, GEORGIA.

MAIL COLLECTION AND DELIVERY BOX.

No. 818,241.

Specification of Letters Patent.

Patented April 17, 1906.

Application filed August 3, 1905. Serial No. 272,507.

To all whom it may concern:

Be it known that I, JOHN IRWIN FULLWOOD, a citizen of the United States, and a resident of Cedartown, in the county of Polk and State of Georgia, have invented a new and Improved Mail Collection and Delivery Box, of which the following is a full, clear, and exact description.

This invention particularly relates to means for safely holding mail-matter that is collected or distributed by mail-carriers traversing suburban or rural mail routes, and has for its object to provide novel simple details of construction for a mail collection and delivery box to be carried in or on a suitable vehicle which affords safe and very convenient means for holding collected mail-matter and also for distributing other mail-matter addressed to patrons living on rural delivery and suburban mail routes traversed by Federal mail-carriers.

The invention consists in the novel construction and combination of parts, as is hereinafter definitely described and claimed.

Reference is had to the accompanying drawings and characters of reference thereon, similar characters designating corresponding parts in all the figures.

Figure 1 is a partly-sectional end view of a mail collection and delivery box embodying details of the invention, a novel supporting-bracket, and a portion of a vehicle whereon the bracket and box are mounted. Fig. 2 is a rear side perspective view of the improved collection and delivery box supported upright by two novel brackets and showing the interior of the box by an opened adjustment of a pivoted section of the casing of the box, which serves as a closure therefor. Fig. 3 is a plan view of the mail-box in closed condition. Fig. 4 is an enlarged transverse sectional view substantially on the line 4-4 in Fig. 3, showing a weatherproof joint formed between the door of the box and one edge of the opening in the box guarded by said door. Fig. 5 is an end view of the improved mail-box embodying a flag or signal to indicate mail for delivery at a point on the route of the mail-carrier. Fig. 6 is a partly-sectional plan view of the mail-box provided with the signaling means; and Fig. 7 is a transverse sectional view substantially on the line 7-7 in Fig. 6, showing a spring-lock that may be employed.

The mail-box is preferably constructed of 55 plate metal and comprises a casing of partially - cylindrical form having a suitable length and diameter, the peripheral wall 10 thereof being closed at each end by transverse walls 10^a, but is open at the normally 60 inner side thereof. A closure for the open side *a* of the casing 10 is in the form of a curved wall 11, having transverse walls 11^a, that are preferably angular on their edges, and at the radial centers of said end walls 65 10^a the walls 11^a are pivoted upon the end walls 10^a, as at *b*. The curvature of the door side walls 11 is such that when the door is rocked on its opposite pivots *b* said wall 11 will move 70 closely to the casing-wall 10 and occupy but little room when in opened condition.

Near one end in the box-body a vertical partition *c* is erected, which appears plainly in Fig. 2, affording a compartment that may 75 be divided into two mail-holders *c'* and *d* by the introduction of a slidable drawer *e* between the end wall 10^a nearest to it and the partition-wall *c*, as shown in Fig. 2. The remaining space within the mail-box is preferably subdivided into three compartments *g* *h* *i* by the central upright partition *k*, which is about half the height of the interior of said box and joins a longitudinally-disposed shelf *m*.

The drawer *e* may be used for holding 85 United States postage-stamps of different denominations to supply patrons therewith, or prepaid envelops may be carried and also placed in the drawer *e* for a like purpose.

The spaces *g*, *h*, and *i* may be utilized for holding assorted mail-matter in packs for their convenient distribution, and newspapers may also be carried and distributed to persons to whom they may be addressed.

In the door-wall 11 a slot *l* is formed, as 95 shown by dotted lines in Fig. 3, it being of a sufficient size to permit the free insertion of letters or the like within the compartment *c'* above the end drawer *e*, that is directly below the slot, the latter being normally covered by a hinged flap-door *l'*. The compartment *d* is designed to hold letters for distribution to patrons.

The door-opening *a* is defined in part by a transverse edge on the casing-wall 10, on which is formed a hook *n*, and on the transverse edge of the door 11^a, which approaches the hooked edge *n* when said door is closed, a

similar hook n' is bent, which will interlock with the hooked edge n and form a closure that will practically exclude the elements when the rockable door 11^a is closed, this detail being plainly shown in Fig. 4.

Preferably the bottom wall 10^b of the casting for the mail-box is flat and may be of wooden - board material faced with plate metal, whereon the lower transverse edge of the door will impinge, and for securing the door in closed condition when the mail-box contains mail that is not being delivered it is preferred to employ a suitable padlock o . (Shown applied in Fig. 1.)

15 As indicated in Figs. 6 and 7, the door 11 may also be held temporarily closed with a spring-pressed latch-bolt p of ordinary form, this being used only for holding the door shut while the box is in use and must be opened frequently for delivery of mail-matter.

20 The improved mail-box may be utilized for collection of mail from patrons along the route by placing it at a convenient point on a post or the like, and thus enable the postman to remove mail-matter from the box that is to be mailed and also to receive mail that is to be delivered. If the improvement is to be used for the purpose just mentioned, it is preferred to mount a signal-arm 12 on one 25 end wall of the door 11 , said arm when rocked into an upright position, as indicated in Figs. 5 and 6 by full lines, indicating that mail is to be taken out of the box either by the postman or by the receiver of mail. When the 30 arm is hanging pendent, no mail is within the box, thus notifying the mail-carrier to that effect.

35 The improved mail-box when used for delivery of mail by a carrier is for service arranged to be carried upon a traveling conveyance, which may be a wheeled vehicle drawn by one or more horses or be otherwise propelled, a four-wheeled vehicle or road-wagon A being shown to illustrate a novel 40 means for the detachable support of the mail-box on the front of the conveyance.

45 As appears in Figs. 1 and 2, there are two similar bracket-frames provided, each embodying the following details: A right-angled bar forms the lower portion of each bracket-frame, the bend r providing a foot-piece 13 and an upright standard 14 . The foot - piece 13 is formed with spaced openings s therein for reception of bolts s' 50 for securing the foot-piece and standard on the bottom of the vehicle-bed, as is shown in Fig. 1, thus disposing each standard 14 closely to the front end wall of the vehicle-body. A extension-arm 15 is provided as a 55 complementary member for each standard 14 , these similar arms each having a longitudinal slot t therein for reception of a clamping - bolt u , that may be inserted through either of a plurality of spaced perforations v , 60 formed in the standard 14 , said bolts that

65 pass through the slots t each having a winged nut w' mounted thereon, that serves to clamp the standard and its extension-arm together when the nut is properly adjusted. Two flanges t^2 are formed on the side edges of each 70 standard 14 , at or near the upper end thereof. These flanges, which loosely embrace respective extension-arms 15 , together with the clamping - bolts u , hold the arms and standards alined edgewise, so that lateral 75 displacement or swagging is prevented. To stiffen the connection between each of the arms 15 and foot-pieces 13 , a diagonal brace 16 is removably secured by its ends, respectively, thereon, this connection for one 80 brace appearing in Fig. 1. The extension-arms 15 are preferably T-shaped, each having a flat wing 15^a projected an equal length forward and rearward from the upper end of a respective extension-arm. The rear wing 15^a on each extension-arm 15 is slotted longitudinally, as shown at w for one wing in Fig. 1, these slots each receiving a clamping-bolt w' , that passes down through the bottom wall of the mail-box and through a respective 90 slot w , receiving on the projecting end a winged nut w^2 , which by its clamping adjustment holds the mail-box securely on the standard extensions 15 .

95 It will be seen that the mail-box may be adjusted forward or rearward to suit the situation by slackening the nuts w^2 and subsequently tightening them when the mail-box is properly positioned. Furthermore, the extension-arms 15 may be raised or lowered, 100 as may be desired, by slackening the nuts w' and after adjusting the box for height again tightening them.

105 The improvement may be carried on a mail-car, an automobile, a sleigh, or any vehicle that is adapted for speedy traverse of outlying streets in a city, town, or over a route in a rural district and enable the proper carriage, careful protection, and accurate delivery of mail-matter it may conveniently 110 carry, and it is obvious that mail collections and supplying of stamps or stamped envelops may also be conducted for convenience of the public living along country roads that are embraced in the Federal rural free-delivery 115 system.

Having thus described my invention, I claim as new and desire to secure by Letters Patent—

1. A supporting - frame for a mail - box, 120 comprising duplicate standards having vertical extensions, and lateral wings on upper ends of said extensions, said wings being securable on the bottom of a mail-box mounted thereon.

125 2. In a dèvice of the character described, the supporting-frame for the mail-box, comprising two upright standards having horizontal base portions, a slotted extension-arm clamped upon each standard by an ad- 130

justable bolt and nut, the slotted extension-
arms each having a slotted horizontal wing on
its upper end, and a bolt engaging said slot
and also engaging the bottom of a mail-box
body for adjustably securing the box on the
standard.

5 In testimony whereof I have signed my

name to this specification in the presence of
two subscribing witnesses.

JOHN IRWIN FULLWOOD.
